UNITED STATES PATENT OFFICE.

ALPHONSE JOSEPH PLÉGAT, OF ALEXANDRIA, EGYPT.

INTERNAL-COMBUSTION ENGINE.

1,373,261.

Specification of Letters Patent. Patented Mar. 29, 1921.

Application filed October 13, 1919. Serial No. 330,213.

To all whom it may concern:

Be it known that I, ALPHONSE JOSEPH PLÉGAT, a citizen of the French Republic, and residing at Alexandria, Egypt, have invented new and useful Improvements in Internal-Combustion Engines, of which the following is a specification.

The present invention relates to an internal combustion engine which is characterized by the fact that, if an element of this engine is considered, said element consisting of two opposed movable cylinders, each cylinder forms one piece with the piston of the opposed cylinder. The engine may work on either the two- or four-stroke cycle. The engine is a rotary engine when the crank-shaft is stationary and is of the fixed type when the crankshaft rotates and the casing of the engine is fixed to a base. A valve-gear, provided in one or in two cylindrical recesses parallel to the axis of the cylinder and formed either inside the piston or laterally of the cylinder, controls the running of the engine.

The invention is shown by way of example, but purely indicatively and in no way limitatively, in the accompanying drawing in which:

Figure 1 represents the combination of one cylinder with the piston opposed thereto;

Fig. 2 is a partial section showing the engine at the end of its stroke, at the beginning of the expansion period, the piston carrying the valve gear, and the engine-shaft being in two parts, each fixed to a stationary support, the engine in this case being shown as a rotary one.

Fig. 3 is a partial longitudinal section of the same constructional form, the engine being at the end of its stroke at the beginning of the exhaust period.

Fig. 4 is a view of a modification.

Fig. 5 a view of another modification.

Fig. 6 a view of a further modification.

On reference to Fig. 1 it will be seen that the cylinder *c* forms one with the opposite piston *p*¹ owing to two lateral extensions *c*², *p*², this being arranged in such a manner as to allow each piston *p*, *p*¹ to be fitted into its respective cylinder *c*, *c*¹.

Each piston is guided, as shown in Figs.

2 and 3, by a crank-pin, and the crank-pins of the two pistons are spaced at an angle to each other of 180° so that expansion takes effect upon two movable faces and has a simultaneous and concerted action at the two extremities of a diameter of the circle of the cranks. As the piston and the cylinder move in opposite directions, they give in combination a stroke equal to twice this diameter of the cranks.

On referring now to Fig. 2, it will be seen that the piston *p* is provided, parallel to its axis, with a cylindrical recess for the reception of a tube *a*³ connected by means of a ring *a*⁴ to the bearing of the engine shaft, or attached by means of bolts, for example, to the wall of the casing *a*, *a*¹ within which the cylinder *c* slides. Within the tube *a*³ is mounted a cylindrical member *p*³ having a long segment *s* fixed to one of its extremities and terminating at the outer end in a rod which again terminates in a crank *t*. This crank engages in a groove running around the ring *q*, which latter rotates around the engine-shaft at a speed reduced in the desired ratio, owing to the fact that the ring *q* carries a toothed rim *q* driven by teeth which latter form an integral part of, or are fixed to, the big end of the connecting rod *b*; the number of these teeth being half that of the rim *q*. The ring *q* therefore makes half a rotation for one rotation of the crank-pin.

The segment *s* constitutes a hollow rotative distributor, the inner portion of which is constantly in communication with the corresponding explosion chamber.

When the engine revolves, the segment *s* is driven by the ring *q* and crank *t*, which rotate it in such a manner that at the moment of suction it presents its aperture opposite the port *l*. This latter is in communication, by way of a passage *a*² formed in the wall of the tube *a*³, with the crank chamber to which the gaseous mixture arrives through the hollow shaft *d* and through the orifices *e*. If desired, the passage *a*² can be placed in direct communication with the carbureter by means of a connection on the hollow shaft of the engine, or again, through the wall of the casing *a*, *a*¹ in the case of a fixed engine. During the two following

strokes the segment is so positioned that the port l is covered, thereby allowing compression and expansion to take place in the cylinder. Finally, during the exhaust stroke, 5 see Fig. 3, the segment s uncovers the port l^1 which is in communication with the passage a^5 formed in the tube a^3 and communicating with the atmosphere. The cylindrical body p^3 carries the sparking plug f .

10 According to another form of execution, which is shown in Fig. 4, the piston carries two cylindrical recesses parallel to its axis instead of one, in each of which there is mounted a tube fixed to the outer casing of 15 the engine. One of these tubes carries the suction valve and is in communication with the carburetor, while the other, which carries the exhaust valve actuated by a cam, communicates with the atmosphere.

20 The distributing devices may also be fitted laterally on the cylinder c , as indicated in Fig. 5, and this arrangement is also within the scope of the invention.

Referring to Fig. 4, the tube a^3 has two 25 internal cylindrical recesses c^2 and c^3 . One of these recesses c^2 which receives the suction valve s^1 communicates with the crank-chamber from which comes the gaseous mixture. The other recess c^3 which contains the exhaust valve s^2 communicates with the atmosphere. These valves s^1 and s^2 are actuated by the cam q^1 having a two-fold acting surface and driven at a reduced speed by the connecting rod end b .

35 In the modification shown in Fig. 5, the cylinder c has a lateral cylindrical recess c^4 parallel to its axis and in constant communication with the interior of the cylinder. In this recess, there is fitted a valve gear similar to that described in Figs. 2 and 3, except for the fact that the grooved ring q^3 which rotates at a reduced speed about the shaft d^1 of the engine is not driven at this reduced speed by the connecting rod end b .

40 A toothed wheel q^2 , whose axis q^3 is fixed on the outer casing of the engine and is engaged by teeth fixed around the shaft d^1 , meshes in its turn with an inner toothed rim on the ring q^5 which carries a number of 45 teeth equal to twice the number of teeth carried by the shaft d^1 of the engine.

Referring to Fig. 6, the cylinder in this case has two lateral cylindrical recesses c^5 , c^6 in constant communication with the interior 55 of the cylinder and each containing a tube a^6 , a^7 fixed to the outer casing of the engine. One of these tubes, a^6 , which contains the suction valve s^3 communicates with the carburetor; the other tube, a^7 , which contains 60 the exhaust valve s^4 communicates with the atmosphere. The valves s^3 and s^4 are actuated at the desired instant by a cam q^4 forming a ring rotating about the engine shaft at a speed which is reduced in the same way 65 as that of the ring q^5 shown in Fig. 5.

In case the engine is fixed by the casing to a base, the crank-shaft may be made of a single piece.

I claim:

1. An internal combustion engine comprising a casing, a pair of cylinders adapted to move toward and away from each other in said casing, a piston working in each cylinder, each piston being rigid with the opposed cylinder, a crank-shaft about which 70 said casing can rotate, means for connecting said pistons to said crank-shaft, a tube mounted in each piston having an admission and exhaust passage to and from the cylinder, a segment mounted in said tube having an aperture adapted to register with 75 said admission and exhaust passages, and means operated by the movement of the pistons for actuating said segment.

2. An internal combustion engine comprising a casing, a pair of cylinders adapted to move toward and away from each other in said casing, a piston working in each cylinder, each piston being rigidly connected to its opposed cylinder, a crank-shaft about 80 which the casing can rotate, a rod connecting each piston to said crank-shaft, a toothed rim rotatable on said shaft, said rim having a cam-groove cut therein, teeth on said connecting rod ends meshing with said toothed 85 rim, the respective numbers of the teeth being in the desired ratio, a tube mounted in each piston having an admission and exhaust passage to and from the cylinder, a segment mounted in said tube having an aperture for registering at suitable times 90 with said admission and exhaust passages and a crank engaging in said cam-groove and connected to said segment.

3. An internal combustion engine comprising a casing, a pair of cylinders adapted to move toward and away from each other in said casing, a piston working in each cylinder, each piston being rigidly connected to its opposed cylinder, a crank shaft about 105 which the casing can rotate, a rod connecting each piston to said crank-shaft, a toothed rim rotatable on said shaft, said rim having a cam-groove cut therein, teeth on said connecting rod ends meshing with said toothed 110 rim, the numbers of teeth on the connecting rods being in the necessary ratio to the number of those on the rim, a tube mounted in each piston having an admission and exhaust passage to and from the cylinder, a segment mounted in said tube having an aperture adapted to register with said admission and exhaust passages and a crank 115 engaging in said cam groove and connected to said segment.

4. An internal combustion engine comprising a stationary casing, a pair of cylinders adapted to move toward and away from each other in said casing, a piston working in each cylinder, each piston being 120

125

130

rigid with the opposed cylinder, a crank-shaft rotatably mounted in said casing, means for connecting said pistons to said crank-shaft, a valve-member mounted in 5 each piston, and means actuated by the motion of the pistons for moving said valve member to distribute the working fluid.

5. An internal combustion engine comprising a stationary casing, a pair of cylinders adapted to move toward and away 10 from each other in said casing, a piston working in each cylinder, each piston being rigid with the opposed cylinder, a crank-shaft rotatably mounted in said casing, 15 means for connecting said pistons to said crank-shaft, a tube mounted in each piston having an admission and exhaust passage to and from the cylinder, a segment mounted in said tube having an aperture adapted to 20 register with said admission and exhaust passages and means operated by the movement of the pistons for actuating said segment.

6. An internal combustion engine comprising a stationary casing, a pair of cylinders adapted to move toward and away 25 from each other in said casing, a piston working in each cylinder, each piston being rigidly connected to its opposed cylinder, a 30 crank-shaft rotatably mounted in said casing, a rod connecting each piston to said crank-shaft, a toothed rim keyed on said shaft, said rim having a cam-groove cut

therein, teeth on said connecting rod ends 35 meshing with said toothed rim, the respective numbers of teeth being in the desired ratio, a tube mounted in each piston having an admission and exhaust passage to and from the cylinder, a segment mounted in said tube having an aperture for registering 40 at suitable times with said admission and exhaust passages, and a crank engaging in said cam-groove and connected to said segment.

7. An internal-combustion engine comprising a stationary casing, a pair of cylinders adapted to move toward and away from each other in said casing, a piston working in each cylinder, each piston being rigidly connected to its opposed cylinder, a 50 crank-shaft rotatably mounted in said casing, a rod connecting each piston to said crank-shaft, a toothed rim keyed to said shaft, said rim having a cam-groove cut 55 therein, teeth on said connecting rod ends, meshing with said toothed rim, the respective numbers of teeth being in the desired ratio, a tube mounted in each piston having an admission and an exhaust passage to and 60 from the cylinder, a segment mounted in said tube having an aperture adapted to register at suitable times with said admission and exhaust passage and a crank engaging in said cam-groove and connected to said segment.

ALPHONSE JOSEPH PLÉGAT.
